D. J. C. Arnold,
Attorney Wm. M. Monroe,

UNITED STATES PATENT OFFICE.

DANIEL J. C. ARNOLD, OF NEW LONDON, OHIO.

DETACHABLE FURNITURE-JOINT.

SPECIFICATION forming part of Letters Patent No. 434,229, dated August 12, 1890.

Application filed January 6, 1890. Serial No. 336,057. (No model.)

To all whom it may concern:

Be it known that I, DANIEL J. C. ARNOLD, a citizen of the United States, and a resident of New London, county of Huron, and State 5 of Ohio, have invented certain new and useful Improvements in Detachable Furniture-Joints, which is especially designed as an improvement upon the invention of Arthur W. Carl, for which an application for a 10 United States patent was filed November 5, 1889; and I hereby declare the following to be a full, clear, and exact description of the invention, such as will enable others skilled in the art to which it appertains to make and 15 use the same.

My invention relates to improvements in the manner of detachably connecting side rails with an end post in the construction of furniture and other devices; and its objects 20 are to strengthen and increase the rigidity of the various parts as well as their durability and lessen the initial cost.

My invention is adapted to the construction of joints where a pair of side rails are 25 detachably secured to a corner-post; and it consists in the employment of a band or plate of sheet metal having its extremities securely attached to the ends of the side rails and having its central or body portion longitudinally 30 divided into two or more portions separated, so as to completely encircle the whole or a portion of the post, and also in the details of construction and arrangement of parts, as hereinafter described, shown in the drawings, 35 and more particularly pointed out in the claim.

In the accompanying drawings, Figures 1 and 2 are isometric views of forms of my improved device. Fig. 3 is a detail of the form 40 shown in Fig. 1, and Fig. 4 is a longitudinal section of the head of the post on line x , Fig. 1.

In the drawings, Figs. 1 and 2 show a form of the device in which the extremities a of the metal strip A are secured in sawed slots 45 in the ends of the side rails C by screws or pins c , and the main body is slotted twice longitudinally, so as to provide a central band A'. This band and the upper and lower 50 portions A² are then bent apart in opposite

directions, the inclosed space thus formed being shaped by a mandrel or die to conform to the outline of the head of the post B, the upper and lower portions A² A² being bent to conform to the inner angle b , while the central band A' is bent outward and forced downward into the saw-kerf b' , which is preferably made with a cylindrical saw, as shown in solid lines, or the band may be made angular, as shown in dotted lines, and two slots be 60 formed in the post at right angles at b^2 . The sawed slots b' or b^2 are preferably made to incline slightly outward, as shown in section at Fig. 4, the effect being to jam slightly the various parts and secure the head of the post 65 without pins or screws. These may be added, however, when necessary.

Fig. 2 shows a form of my invention in which the several bands are designed to encircle the exterior of the post, the extremities a being attached by screws to the ends of the rails. To make the rigidity of the parts complete and to prevent the screws from wearing loose in the rails, the ends of the extremities a of the strip A are bent inwardly 70 into shallow saw-kerfs in the rails C, as c' , which prevent any lateral motion of the parts. This metal joint, being struck from a single plate and requiring no trimming, makes an extremely simple, strong, and durable joint not 75 liable to become detached by accident, but readily disconnected for transportation and packing.

Having thus described my invention, what I claim as new, and desire to secure by Letters Patent, is—

In a corner-joint for furniture or other purposes, a plate or band of metal secured to the extremities of the side rails at either end and with its central portion divided longitudinally 90 into one or more strips, as A' and A², the said strips being integral portions of the plate and separated laterally to form an opening inclosing an integral portion of the head of a corner-post.

DANIEL J. C. ARNOLD.
